MACHINE FOR USE IN APPLYING PRESSURE
TO SHOE BOTTOMSEuclid I. La Chapelle, Brockton, Mass., assignor
to United Shoe Machinery Corporation, Pat-
ersen, N. J., a corporation of New Jersey

Application April 16, 1937, Serial No. 137,295

7 Claims. (Cl. 12—33)

This invention relates to machines for use in applying pressure to shoe bottoms and is illustrated herein with reference to cement attaching soles to shoes.

5 In cement attaching soles to shoes, particularly shoes having relatively high insteps and deeply arched shank portions, it is desirable to apply to the shank portion of the shoe bottom pressure considerably in excess of what is applied to the 10 forepart in order to conform the sole properly to the arch in said shank portion and to cause the sole to become firmly attached to the shoe bottom at that portion. When this operation is performed with the aid of many of the pressure applying devices now in use such, for example, as a single yieldable pad or an inflated bag, the high pressure required to shape the shank portion of the shoe cannot be properly controlled and restricted to the shank portion alone with the result 15 that excessive pressure is applied to the forepart of the shoe.

This excessive pressure at the forepart of the shoe bottom is always detrimental to the shoe and may result not only in injuring the appearance 20 of the shoe bottom at the forepart but also in subjecting the upper materials at the edge of the insole, especially in the vicinity of the ball line, to such a strain or compression that the upper is liable to crack or break during the wear 25 of the shoe.

Objects of the present invention are to provide 30 an improved machine for cement attaching soles to shoes by the use of which the difficulties referred to above are eliminated.

35 With these objects in view the invention provides, in accordance with one of its features, a member for applying pressure to the rear portion of a shoe bottom, a separate member for applying pressure to the forepart of the shoe bottom, and 40 means for predetermining or limiting the pressure that is to be applied to the forepart of the shoe bottom by said separate forepart member. As illustrated, the rear pressure applying member is arranged to apply pressure to the shank 45 and heel portions of the shoe approximately from the ball line rearwardly and is shaped to conform to the longitudinal contour of the shank and heel portions of the shoe bottom. The forepart pressure-applying member may have a substantially 50 flat sole-engaging surface.

In accordance with further features of the invention the shank and heel pressure applying member may be provided with individual means for controlling the pressure exerted thereby on 55 the shoe bottom, a support may be provided for

the shoe which will allow the shoe to pivot about a horizontal axis located substantially over the ball line of the shoe, thereby permitting the shoe to adjust itself automatically to the shank and heel pressure applying member, and the forepart pressure applying member may be arranged for pivotal movement relatively to the shoe bottom so that it can automatically adjust itself to the plane of said shoe bottom during the pressure applying operation.

With the above and other objects and features in view the invention will now be described in connection with the accompanying drawings and thereafter pointed out in the claims.

In the drawings,

Fig. 1 is a front elevation, partly broken away and in section, of the machine embodying the present invention;

Fig. 2 is a section taken on the line II—II of Fig. 1;

Fig. 3 is an end elevation looking from the left in Fig. 1;

Fig. 4 is a section taken on the line IV—IV of Fig. 1 showing the pressure applying members in plan view;

Fig. 5 is a front elevation similar to Fig. 1 showing the rear pressure applying member in operative position; and

Fig. 6 is a similar view showing both pressure applying members in operative position.

The machine comprises a rectangular frame 10 supporting, at its upper end, a plate 12 to which is secured, about midway of its length, a U-shaped bracket 14 which extends transversely across the plate 12 and has a bifurcated projection 16 extending downwardly from the center of its cross portion. Pivoted on a pin 18 in the bifurcated end of the projection 16 is a shoe support or jack 20 comprising a substantially L-shaped arm 22 one leg 23 of which extends downwardly toward the plate 12 and is provided with a curved shoe engaging member 24 having a concave lower surface in position to engage the forepart of a shoe and support it against pressure applied to the bottom of said forepart.

The other leg of the L-shaped arm 22 of the jack extends upwardly and to the right, as viewed in Fig. 1, and is provided on its upper edge face with a series of notches 26. Slidably mounted on this leg of the arm 22 is a member 28 provided with a downwardly extending lug 30 to which is pivoted by a pin 32 a last engaging member 34 arranged to support the heel portion of a last on which the shoe is mounted, the shoe being held on the jack, for example, by hand or in some

other convenient manner. The last and shoe engaging members or abutments 24, 34 are illustrated herein as conventional last and shoe supporting members and the exact construction of these abutments could, of course, be varied within the invention.

The slide member 28 is provided on its upper side with a leaf spring 36 having a projection 38 (Fig. 1) thereon for engaging one of the notches 26 and thus holding the last engaging abutment 34 in such a position that the forepart of the shoe will be engaged at the proper location by the forward abutment 24. The abutment 34 may be adjusted relatively to the arm 22 by lifting the leaf spring 36 and sliding the member 28 along the arm until the projection 38 engages a notch in the proper position for the size of shoe being operated upon.

As shown in the drawings, the machine is adapted to operate upon a shoe having its outsole temporarily secured thereto or "spotted" by a suitable tacky adhesive such, for example, as rubber cement applied to central portions of the sole and shoe bottom so as not to interfere with the application of the sole attaching cement to the marginal portions thereof. Before the shoe is mounted on the jack 20, the sole and shoe bottom will have been treated on its marginal portions in the usual manner with sole attaching cement such, for example, as pyroxylin cement, in which case the cement will have been activated by a solvent to render it adhesive, and the sole will have been properly positioned on, and temporarily stuck to, the shoe bottom by the tacky rubber cement.

The supporting plate 12 is provided on its lower side with a pair of bosses 40, 42 which are bored vertically and threaded to receive, respectively, vertical screws 44, 46. The screw 44 is arranged to underlie the heel portion of a shoe mounted on the jack 20 and at its upper end the screw is rotatably connected to a member 48 having an enlarged portion to which is bolted a plate 50 arranged to underlie the shank and heel portions of the shoe and shaped to conform generally to the longitudinal contour of those portions of a shoe bottom. The plate 50 has secured thereto in any usual or convenient manner a pressure applying member 52, preferably a yielding pad of more or less resilient material such, for example, as rubber, the pad being of sufficient thickness to permit the sole and shoe to sink into it somewhat during the pressure applying operation, thereby conforming the pad to the curvatures of the shank and heel portions of the shoe bottom. At its forward or left-hand end, as viewed in Fig. 1, the plate 50 is provided with a downwardly extending pin 54 which has a sliding fit in a hole 56 in the supporting plate 12 and prevents the plate and pad 52 from turning when the screw 44 is adjusted heightwise in the supporting plate.

Below the supporting plate 12 the screw 44 has fastened thereto by a set screw 58 a stop collar 60 and its lower end has pinned thereto a hand wheel 62 whereby the screw may be rotated to move the pad 52 toward and away from the shank and heel portions of a shoe on the jack. The upward movement of the screw 44 may, of course, be limited by the position of the stop collar 60 on the screw and, accordingly, the pressure which may be applied to the shank and heel portions of the sole and shoe may thus be limited to a predetermined amount.

It will be seen from Figs. 1 and 4 that the for-

ward or left-hand ends of the pad 52 and plate 50 terminate at substantially the ball line of a shoe mounted on the jack 20 and that these left-hand ends extend across the shoe bottom at an angle which corresponds substantially to the angle of the ball line of the shoe when seen in plan view.

The screw 46 at the left-hand side of the plate 12 (Fig. 1) is provided at its lower end with a hand wheel 64 and at its upper end is rotatably connected to a member 66 bolted to the lower side of a plate 68, the left-hand end of the plate 68, as viewed in Fig. 1, having secured thereto a downwardly projecting pin 70 which has a sliding fit in the supporting plate 12 and thus acts to prevent the plate 68 from turning as the screw 46 is threaded upwardly and downwardly in the boss 42. The plate 68 is provided at its opposite sides with upstanding ears 72 between which is pivotally mounted by pins 74 a pressure applying member or plate 76 provided with a resilient pressure applying pad 78 of substantial thickness. This arrangement permits the pressure applying member 76 and pad 78 to adjust themselves automatically to the angle of the forepart of the shoe bottom when the pad is moved into engagement with said forepart by the screw 46. Below the supporting plate 12 the screw 46 carries a stop collar 80 secured thereto by a set screw 82. The position of the collar 80 on the screw 46 limits upward movement of the screw and thus limits or determines the pressure that can be applied to the forepart of the shoe by the pad 78. Preferably the collar 80 on the screw 46 is adjusted so that the rear pad 52 will be caused to apply relatively heavy pressure to the entire shank and heel portions of the shoe bottom whereas the collar 80 on the screw 46 is positioned so that the pressure of the pad 78 on the forepart of the shoe bottom will be relatively light, the exact pressures, of course, depending on the type of shoe being operated upon.

In applying pressure to shoe bottoms by the aid of the machine disclosed herein a shoe a is mounted on the jack 20 and held by the operator or otherwise with the outsole c of the shoe temporarily secured to the shoe bottom by tacky rubber cement. The shoe is thus located in position over the forepart pressure applying member 78 and the shank and heel pressure applying member 52, and is freely movable about the pivot 18 which, as illustrated, is preferably located over, or slightly forwardly of, the ball line of the shoe. The operator rotates the screws 44 and 46 by their hand wheels to move the pressure applying members 52, 78 into engagement, respectively, with the shank and heel portions of the shoe bottom and with the forepart of the shoe bottom.

Preferably, but not necessarily, the shank and heel pressure applying member or pad 52 is moved into engagement with the corresponding portions of the shoe bottom before the forepart member 78 is moved against the forepart of the shoe, thereby causing the shoe to swing in a counterclockwise direction (as viewed in Figs. 1 and 5) about the pivot 18 until the shank and heel portions of the shoe bottom are located in parallel relation to and are engaging the entire work engaging surface of the pad at which time the upper edge face of the arm 22 of the jack engages the projection 16 above its bifurcated portion and, by preventing further movement of the jack and shoe in a counterclockwise direction under the action of the pressure applying mem-

ber 52, causes pressure to be applied to the shank and heel portions of the shoe. Movement of the shoe in said counterclockwise direction to bring the arm 22 into engagement with the projection 16 also positions the forepart of the shoe bottom in a substantially horizontal plane so that pressure applied to the forepart of the shoe bottom by vertical movement of the screw 46 will be directed substantially at right angles to the plane 10 of the forepart of the shoe bottom.

The pressure applying member 78 at the forepart of the shoe is moved upwardly by the screw 46 until it engages the shoe bottom and applies pressure thereto, this pressure, as stated above, 15 being limited as desired by engagement of the stop collar 80 with the boss on the supporting plate 12. If the forepart of the shoe bottom is at a slight angle to the surface of the pressure applying pad 78, the latter can adjust itself automatically to the forepart of the shoe by reason of the pivotal arrangement of the plate 76 between the ears 12. As shown in Fig. 4, the forward plate 76 and pad 78 register at their right-hand ends with the angle of the adjoining ends of the 20 shank and heel plate 50 and pad 52 so that the pressure of the pad 78 is applied to the entire forepart of the shoe bottom from the toe end rearwardly to the ball line.

After the desired pressure has been applied for 30 a sufficient period to the entire shoe bottom, the pressure applying members 52, 78 may be moved downwardly away from the shoe through rotation of their actuating screws and the shoe with its sole permanently attached thereto removed 35 from the jack. Since with the aid of the present machine the pressure that is applied to the shank and heel portions of a sole and shoe, that is, from the ball line rearwardly to the heel end, is considerably greater than the pressure that is 40 to the forepart of the shoe or from the ball line forwardly to the toe end, it will be seen that the shank portion of the sole may be properly cemented to the corresponding portion of the shoe bottom without the application of excessive pressure to the forepart of the shoe bottom. Thus, 45 all danger of injury to the forepart of the shoe bottom or to the shoe upper, particularly in the vicinity of the ball line of the shoe, is eliminated.

Having described my invention, what I claim 50 as new and desire to secure by Letters Patent of the United States is:

1. A machine for applying pressure to shoe bottoms having, in combination, means for supporting a shoe, a single member for applying 55 pressure to the rear portion of the shoe bottom from its ball line to its heel end, another single member for applying pressure to the forepart of the shoe bottom from said ball line to its toe end, and means for controlling the pressure that can 60 be applied to the forepart of the shoe bottom by said member.

2. A machine for applying pressure to shoe bottoms having, in combination, means for sup-

porting a shoe, a single member movable relatively to the shoe for applying pressure to the rear portion of the shoe bottom from its ball line to its heel end, another single member movable relatively to the shoe for applying pressure to the remainder of the shoe bottom, and means for varying the pressure to be applied to the shoe bottom by each of said movable pressing members. 5

3. A machine for applying pressure to shoe bottoms having, in combination, means for supporting a shoe, a single member for applying pressure to the entire rear portion of the shoe bottom, a separate member for applying pressure to the forepart of the shoe bottom, means for moving said pressure applying members toward the shoe to apply pressure thereto, and means carried by said moving means for positively controlling the pressure to be exerted respectively by said members on said portions of the shoe bottom. 10

4. A machine for applying pressure to shoe bottoms having, in combination, means for holding a shoe, a member for applying pressure to the shank and heel portions of the shoe bottom, a separate member for applying pressure to the entire forepart of the shoe bottom, and adjustable means for controlling the amount of pressure to be applied by each of said pressure applying members to the shoe bottom. 15

5. A machine for applying pressure to shoe bottoms having, in combination, a jack for supporting a shoe, a single member for applying pressure to the shank and heel portions only of the shoe bottom, a separate member for applying pressure to the entire forepart of the shoe bottom, separate means for actuating each of said 30 pressure applying members, and means individual to each actuating means for determining and positively limiting the pressure to be applied by each pressure applying member to the shoe bottom, said limiting means being capable of adjustment to vary its limiting action. 35

6. A machine for applying pressure to shoe bottoms having, in combination, means for holding a shoe, a member for applying pressure to the entire shank and heel portions of the shoe bottom, 45 a separate member for applying pressure to the entire forepart of the shoe bottom, and means for operating each of said pressure applying members independently of the other.

7. A machine for applying pressure to shoe bottoms having, in combination, a jack for supporting a shoe, a member for applying pressure to the entire rear portion of the shoe bottom, including its heel portion and a separate member for applying pressure to the entire forepart of the shoe bottom, said separate member being constructed and arranged to adjust itself automatically to the plane of said forepart and said first-mentioned member being located in a predetermined position relatively to the plane of said rear portion. 55

EUCLID I. LA CHAPELLE.
